AUTOMATIC CUT-OFF TOOL HAVING VARIABLE SPEED DRIVE FOR COILING MACHINES

Corrado Boschiero, Milan, Italy, assignor to Simplex-Rapid, Milan, Italy, a corporation of Italy

Filed Mar. 8, 1961, Ser. No. 94,339

Claims priority, application Italy Dec. 17, 1960

2 Claims. (Cl. 153—65)

Coiling machines for the manufacture of every type and shape of springs (tensile, compression, cylindrical, conical, biconical, right-hand, left-hand, and similar types) are commonly known on the market, and in which the wire from which the spring is to be manufactured is fed through hardened steel guides by one or more couples of feed rollers suitably seated on two suitably distanced and adjustable grooved blocks which determine the required, bending radius of the spring. The development of the spring depends on the time, on the basis of which, the feeding of the wire is effected prior to the interruption of the feeding, and after which, with the wire stationary, the cutting tool or knife is lowered in order to cut the wire. The wire is then made to advance for a distance equal to the development length of the next spring.

It is commonly known to those skilled in the art to which the present invention pertains, that any type of spring is subjected to stress fatigue, and that such material stress, after a given period of time or cycles provokes breakage of the spring.

Many factors contribute towards the breaking of springs, depending from the homogeneous characteristics of the material, of the heat treatment to which it has been submitted, and the processing system employed in the manufacture of the spring.

Omitting or leaving out of consideration the first two causes, it has been found that a spring usually breaks almost always in the first coils, and which goes to indicate that the material is subjected to major stress during the early part of the winding operation, and that is to say as soon as the material has commenced to be fed forward. This is due to the instantaneous acceleration, and surge force to which the wire is subjected, and especially when the wire has a small diameter. This yielding is later aggravated by the continuous bending stress made upon the flexible qualities of the wire caused by the helicoidal folding of the wire. This is particularly the case with springs having a small bending radius. This defect in the manufacture of springs is also the cause of inconsistent load bearing capacities in springs of the same size.

All these defects become abolished according to the present invention, by eliminating the interruption in the feeding of the wire heretofore necessary with this type of machine to effect the cutting operation of the wire at a pre-established length thereof that is to say by arranging that the cutting-off operation of the wire takes place simultaneously with the feeding operation. In this way, all of the periods of non-operation, due to the discontinuance of the wire feed, are eliminated, and accordingly the output production is increased. For this purpose a mechanism suitable for accomplishing this operation is provided.

Therefore, all lost time derived from the continuous interruptions in feeding operations are eliminated, and at the same time increasing the production output of the springs, this being achieved with the use of a knife or mobile cutting-off tool, and having a speed equal to or greater than the feed rate of the wire. This movement is carried out in the same direction as the discharge outlet direction of the spring, and that is to say in the opposite direction to the feed direction of the wire.

It remains understood that said movement of the knife

2

could be in an alternating straight line, circular, oscillating, or similar motion, inasmuch as one of the characteristics of the invention is that said knife when in the cutting position is furnished with a movement, comprised of a first movement equal or similar to the wire already spring wound, and having a speed as defined above, and a second penetrating movement almost perpendicular to the first with which to effect the cutting-off of the wire.

Another feature of the invention is contained in the provision of a device to command the cutting-off knife at the exact moment when the wire has to be cut-off, inasmuch as inexactness in this operation would cause a greater or smaller overall development length of the spring, because the feeding of the wire continues during the cutting-off operation.

A further aim of the invention is to provide a driving device suited to supply the cam carrying shaft with a practically infinite range of rotary speeds.

Another aim of the invention is to provide a means suited to adjusting the rotary speed of the cam shaft, having the adjustment effected from the exterior, and without interruption to the movements of the machine and with direct reading on a suitably calibrated dial. This is obtained by substituting the gear train used up to the present day, and which has to be suitably arranged for each length and pitch of spring, by means of any type of variator which controls the cam shaft through a practically infinite range of speeds. This latter, in turn, through a system of levers, operates in an intermittent manner, the cutting knife which receives its motion from a coupling means coupled to the main drive. In this manner the cutting knife can be instantaneously controlled at a speed equal or greater to that of the feed wire speed.

The adjustment of the speed of the cam shaft obtained through the aforesaid speed variator, which in turn receives its motion through the one unique drive motor which feeds the wire independently of said vibratory, can be obtained by means of a hand wheel acting on the variator, and which is connected to the index of a suitably calibrated graduated dial.

A form of the embodiment of the present invention, given for illustration purposes, and not limited to the scope of the invention is given as follows and with reference to the attached drawings in which:

FIG. 1 is a side view of the winding machine for the production of springs in accordance with the present invention.

FIG. 2 is a front view of the same partially opened to give an interior view.

FIG. 3 is a section along line A—A of FIG. 4 of a mechanical clutch for the transmission of the rotary movement derived from a motor, through a series of gears, based on the control drive given to the clutch mechanism by a cam to said clutch, which operates the cutting-off knife through a system of levers.

FIGS. 4 and 5 are both a front view of said mechanical engager or clutch in the respective positions of engagement and disengagement.

FIGS. 6 and 7 respectively, show a front view of said cam drive system in the disengaged and engaged positions.

The winding machine for the manufacture of springs in accordance with the present invention comprises a body principally composed of a plate and frontal upright mounting 1, and a rear plate and mounting upright 1', together with a base 2. On the base 2 is installed a motor 3 the outlet shaft of which drives a pulley 5, by means of a pulley 4, keyed onto the outlet shaft of the motor, said pulleys being connected up by drive belt 6.

On a shaft 7, on which is fitted pulley 5, there is also a key fitted gear 8, which meshes with gear 9, which in turn transmits the rotary motion, through the inter-

mediary gear 10, to rollers 11 and 12 which draw in the wire 13, in collaboration with two oppositely situated rollers 14, and 15, which are held tightly against the two underlying rollers 11 and 12 by the adjustable springs 16. Said rollers 11, 12, 14, and 15 in hardened steel are furnished with peripheral grooves for the drawing of the wire.

From the roller 12, the motion is transmitted through gears 17, 18, 35, 20 and 21 which have a given ratio to the two perfectly equal gears 22, which eccentrically carry a 10 turret 58 which supports the knife 23, being adjustable in height, and such knife remains always in a given position being preferably vertical, inasmuch as the two gears are perfectly similar to each other. In this manner the cutting knife can execute a circular motion in correspondence with the eccentricity value, and with a speed ratio in correspondence with that of the speed of the wire feed. This velocity is preferably equal or greater than that of the speed of the wire feed rate. The cutting-off knife cuts off the helicoidal wound wire by means of the adjustable channelled blocks 56 in collaboration with a counter-knife 57.

The rotation of the cam shaft 24 is changed by means of a speed variator 25 having an infinite range of speeds. Said speed variator is driven in a rotary motion by means of a gear engagement 26, which is keyed onto the gear shaft 9. From gear part 26, the movement is transmitted by a chain 27, to a gear drive 28, which in turn transmits the movement to a toothed wheel 29 by means of a belt drive 30, of the pulley system 64—65, or other member of the variator. From gear 29, the movement is transmitted to another gear 31, on which shaft is fitted gear 32, which is connected by means of chain 33, to gear 34, keyed onto the cam shaft 24.

The movement of rotation of gear 29 allows for the periodic rotation of the intermediary gear 20, by means of an instantaneous coupling of any suitable type and operated by one of the cams on the cam shaft.

For example an instantaneous type of coupling can be constituted by an electro-magnetic coupling (not shown) in the drawing as these devices are commonly known to those skilled in the art to which the present invention pertains). Whilst this type of coupling is very suitable due to the fact that it is instantaneous, it is subject to wear, and in such a manner that after a given period of time becomes unusable and has to be substituted.

Therefore a mechanical type of coupling means has been proposed and illustrated, and which whilst having a rather less instantaneous action, is perfectly suitable to the purpose, and of almost unlimited wearing qualities, as well as of reliable operating capacity. It is easy to understand the importance of providing for this coupling means when considering the fact that the drive action of the knife depends on it, and that the feeding of the wire being interrupted, a delay or anticipation in operating the movement of the knife, which remains stationary during the winding phase, could cause a variation in the length of the spring. The mechanical coupling which forms part of the present invention is a multiple tooth device having multiple pawls which have the function of engaging the coupling means controlling the cutting-off tool in any tooth position of the coupling means, instantaneously at the completion of every revolution of the cam shaft, operated, by the velocity changer.

This coupling means comprises a gear 35, which is in mesh with gear 18, which continually transmits the motion deriving from the already mentioned gears coupled to motor 3; said gear 35 is free with respect to shaft 37, and is provided with internal saw teeth 35', a gear 36 keyed onto shaft 37 in mesh with gear 20, an external disc plate 38 keyed onto shaft 37, and engageable by means of a pin 41 with an internal disc plate 39 freely mounted on shaft 37 and having a plurality of slits 40, of a number different to that of the saw teeth, and of the same number of pawls 42 having part semi cylindrical por-

tion 42", a horizontal arm 43 at the upper end of the cylindrical portion 42' of the pawl 42 ending with a cylindrical upward pin 43' which engages in the respective slit 40 of the internal disc plate 39. Between each pin 43' and the right end (see FIG. 4) of each slit 40 there is provided a spring 44, which tends to push the respective pin 43' towards the other ends of slit 40.

The operation of this mechanical coupling means is as follows: As the cam follower 45 pivoted on a pin 46 encounters with its end in contact with cam 48a step 47 of cam 48 mounted on the cam shaft 24, it carries out a clockwise movement (FIG. 6) causing cranked lever 49 to be oscillated in a counterclockwise direction against the action of the respective compression spring 50, then arm 51 pivoted on a pivot 52, under the action of tension spring 53 which is in a stressed condition in FIG. 6, rotates in a counterclockwise direction bringing into rotation the internal disc plate 39 by means of pin 41. With the consequent counterclockwise rotation of slit 40 in inner disc 39, the pins 43' which are in the disengaged position against the respective end of slits 40 opposed to those on which springs 44 rest, tend to maintain themselves in said position under the influence of the respective springs 44. This provokes therefore a rotation of pawls 42 until one of which through its semicylindrical portion or section engages the cavity of one of the saw teeth 35' in continuous rotation. In this manner pin 43' of the pawl 42 in engagement with a saw tooth operates, by pressing against the end of the respective slot 40, the inner disc 39. This disc 39, through pin 41 and arm 51 which is coupled through pivot 52, to plate 38, rotates said plate. This plate, being keyed to shaft 34, rotates gear 36 which is keyed to the shaft 34. Gear 36 in turn transmits the rotation to gear 20 and thus the operating motion to the cutting-off knife 23.

After one turn of the external disc 38, the arm carried by this latter comes again into contact with the stop constituted by the crank lever 49. The external disc 38 continues to rotate extending the spring 53, whilst pin 41 remains stationary, and therefore also stops the movement of internal disc plate 39. The pawls 42 through its lower portion 42" continue to be drawn along by the saw teeth, whilst pins 43' remain stationary; therefore the semi-cylindrical portion 42" revolves around itself causing it to be freed from its seat in the cavities of the saw teeth, and shaft 37 is brought to a standstill.

In order to block gear 36 always in a given position, a roller 59 is provided carried by an arm 62 pivoted on a pin 63; said arm is subjected to the action of a spring 61. Said roller 59 under the action of spring 61 fits into a recess 60 provided in said gear 36 in such a manner as to block it. Arm 62 with the respective roller is necessary in that, if there were no stopping means provided for shaft 37 when the whole assembly returns into the disengaged position, spring 53 would tend to rotate all the assembly in a clockwise direction, and particularly disc plate 38: in such a manner also pivot pin 52 is moved and accordingly lever 51 changes position.

In the meanwhile, also shaft 37 which draws along pawls 42, continues to rotate under the action of spring 53. However disc plate 39 does not revolve, and also pin 41 remains always in the same position. Pawls 42 therefore rotate around their axes, and thus cause the clutch or joint to be operated only for sufficient time in order that arm 51 assumes a disengaged position again.

As can be easily seen, the greater is the number of pawls 42, the more instantaneous will be the engagement. The time interval for the engagement and disengagement is equal to the interval between one tooth and another divided by the number of said engaging pawls.

The adjustment control of the overall development of the spring to be manufactured is therefore the time interval between one engagement and another of the

cutting-off tool, and depends on the speed assumed by the cam shaft controlled by the speed variator.

Said speed can be continuously changed without interrupting the advancement of the wire or the rotation of the cam shaft. The rotary speed of the cam shaft, and therefore the development of the spring or length of the wire which is needed for a spring can be directly read and regulated by manipulating the variator control wheel 54, observing such values on a dial 55. The pointer of the dial 55 is directly connected to the hand wheel 54 by means of the transmission 66, 67, 68. Then the pulley 68 acts on a pulley 69 of a conventional variator provided by the two pulleys 64 and 65.

In this manner, the machine has to be regulated simply on the basis of the development of the spring, and which can be read on the dial 55, and it is no longer necessary to calculate the gear train to be mounted.

The attached drawings do not show the various devices and transmissions for the production of helical springs, right-hand, left-hand, and similar types, as these are commonly known and do not enter into the scope of the invention.

Whilst a specific form of embodiment of the present invention has been described and illustrated, it is understood that various modifications and changes can be evolved without exceeding the scope limits of the present invention as it is understandable that the type of movement of the cutting off tool, the engaging device for the tool, and the arrangement of the various operating units, as well as the type of variator employed have no importance in this specific regard.

What I claim is:

1. In a winding machine for the manufacture of springs, a cutting-off tool having a normal cutting movement at regular intervals, a speed variator for controlling the movements of the cutting-off tool, a motor connected to the speed variator, a coupling for controlling the cutting-off tool movement, said coupling being engageable or disengageable and which coupling includes: a shaft having a gear mounted on it and which, through other gears, transmits its movement to the cutting-off tool, an external disc plate, an internal disc plate freely rotative around the shaft and having a plurality of slits

arranged around a common circumference, the two disc plates being connected to one another by means of a pin, a second gear in constant mesh with the first-mentioned gear, the internal periphery of said second gear having multiple saw teeth in a number different from the slits in the internal disc plate, a number of pawls equal in number to the number of slits, said pawls having semi-cylindrical extremities in contact with the second gear and also having an arm provided with a pin engaged in the slits, a spring located in each slit between an extremity of the same and a respective pin, an arm (51) arranged on the external face of the external disc plate and pivoted on a pivot pin, a tensile spring anchored externally to the free end of the arm, and a roller carried by a pivoted spring-biased arm (62) and urged into a recess on the periphery of the second gear.

2. In a winding machine for the manufacture of springs and which machine includes means for feeding spring-forming wire, the improvements comprising a cutting-off tool having a cutting movement at regular intervals, means for applying movement to the cutting-off tool to move said cutting-off tool in the direction of winding of the spring-forming wire and with a speed at least equal to the rate of speed of the wire whereby the feeding of the wire is not interrupted during the cutting operation, a coupling for controlling the cutting-off tool movement, means for controlling the engagement or disengagement of said coupling including a cam, a cam follower located between the cam and coupling, said cam follower having one end resting on the cam and its other end resting on the end of a crank lever (49), the other end of the crank lever coming into contact with an arm (51) to act as a stop for said arm.
